UNITED STATES PATENT OFFICE.

JAMES E. GRASSMANN, OF COLUMBIA TOWNSHIP, HAMILTON COUNTY, OHIO.

PRINTING-FORM.

1,260,976.

Specification of Letters Patent. Patented Mar. 26, 1918.

Application filed September 22, 1916. Serial No. 121,548.

To all whom it may concern:

Be it known that I, JAMES E. GRASSMANN, a citizen of the United States, residing in Columbia township, in the county of Hamilton and State of Ohio, have invented certain new and useful Improvements in Printing-Forms, of which the following is a specification.

My invention relates to printing, and its 10 object is to minimize the amount of type metal in printing forms that are to be retained for any considerable period of time, and more especially in those forms made up of solid lines.

15 My invention consists in the combination of parts and in the details of construction and arrangement of parts as will hereinafter be more fully described and claimed.

In the drawing:

20 Figure 1 is a plan view of a printing form embodying my invention, being represented as with the middle parts broken away;

Fig. 2 is an end elevation of the same;

25 Fig. 3 is a vertical cross section on a plane corresponding to the line 3—3 of Fig. 1;

Fig. 4 is a side elevation of the same, and

30 Fig. 5 is a vertical longitudinal section on a plane corresponding to the line 5—5 of Fig. 1.

As I prefer to construct my invention, the solid lines of type 1 are reduced in depth as 35 much as is compatible with the requisite strength, and the provision at the ends of adequate securing means. As herein shown, the latter provision comprises V-shaped notches 2 opening from the ends of the type-lines or bars 1 inwardly thereof; the 40 depth of the type 2 being only sufficient to leave a lug 3 of metal below the V-shaped notch which will have the strength to sufficiently resist displacement of the type-bar in use, when suitable securing means engage above it in the notch 2; and the bar being of just sufficient depth to leave a lug 4 above the notch 2, which will afford a sufficient support for the type or other printing face adjacent to the respective end of 45 the type-bar.

It will be understood that such type-lines or bars 1 as are above described may be made by cutting off the lower parts of type-high type lines or bars as they are made in 50 solid type-line casting machines, and the notches 2 may be cut in the ends by suitable

machinery; or the operation of the type-line casting machine may be so altered as to produce initially the type-line or bar of the reduced height, and with the notches 2 formed in its ends in the casting process. Such altered construction and operation of the machine for this purpose, not being a part of the present invention, need not be further described herein.

If the type-lines or bars be cast type-high, as usual, the first edition of the work may be printed from them while they are in this condition; and then they may have the surplus metal removed, after it is found that the form is to be retained for printing possible future editions of the work. It will be understood that my invention is provided for use in those numerous instances where the contemplated demand for the work does not warrant electrotyping; but, nevertheless, there is a possible demand for limited future editions, which warrants the retention of the form.

The type-lines or bars 1, formed as above described, may be assembled with suitable leads or slugs 5, also correspondingly reduced in depth and notched at the ends like the type-bars or lines 1.

The composition of this reduced height or depth is then provided with a backing made up of pieces of various widths, such as the pieces 6, 7 and 8 shown in Figs. 2 and 3, after the manner of providing ordinary "furniture". These backing strips run at right angles to the type-lines or bars 1, and are of just sufficient height to hold the type faces at the normal type height. This height is usually seven-eighths of an inch; it may be stated that the depth of the type-line or bar 1 from the type face to its lower side, may be about one fourth inch; leaving the depth of the backing strips 6, 7 and 8 in this case, five-eighths of an inch. It will be understood that the backing may be made up of a single piece, or more pieces than herein shown, the desired result being the making of the backing conterminous with the type-bars or lines 1 at the sides of the form. It will be seen that these dimensions depend upon the width of the column in the work to be printed; and where columns of definite widths are to be provided for in frequent instances, the backing may be carried in stock in single pieces of the required widths. Also, the lengths of the pieces of backing may be determined by the height

of the column or page in each instance, and one continuous piece of backing or a number of pieces making up the required length, may be utilized.

- 5 At the top and bottom of the column of composition, slugs 9 are placed, extending up at least past the lower sides of the notches 2 in its middle part, and having its end parts 10 of its upper edge beveled to accurately aline with said lower sides of the notches, when the lower edge of the slug is even with the bottom of the backing. The ends of the slugs are conterminous with the ends of the type-lines or bars 1, and with
- 10 the sides of the backing. These slugs thus hold the composition together longitudinally of the form.

Along opposite sides of the form are placed clip-rules 11, each comprising a main, 20 flat, upright part 12, and an upper, narrower, horizontal part 13 at right angles to the part 12. The main part 12 lies flat against the sides of the backing with its lower edge even with the bottom of the backing, and lies along the ends of the lower lugs 3 of the type-lines or bars, with its upper horizontal part 13 extending into the notches 2, and located at exactly the right height to have the edge of this part 13 engage snugly 25 in the angle or crotch of the V-shaped notch 2 so as to hold the type-line or bar 1 firmly against any upward or lateral displacement. It will be seen that the thickness of each clip-rule lies outside the respective side of 30 the form; and the column rules, inserted when more than one column is used on a page, will be spaced away from the ends of the lines the amount of this thickness. I find that by having the clip-rules of a thickness 35 of two "points", they are of ample strength and give about the right spacing of the column rules under the above circumstances.

These clip-rules may be of brass, such as 45 rules are usually made of, and while the slugs 9, as shown, would usually be of type metal, it will be understood that brass rules of the proper width and length, and with their upper corners properly shaped, may be 50 substituted for these slugs; in which case they need not be thicker than the clip-rules 11 at the sides. The backing may be either of wood or inexpensive metal, or any other suitable inexpensive material to afford the 55 proper foundation for the type-lines or bars when subjected to the heavy pressure in the printing press.

The composition, put together as above described, may be held together by any suitable means, for storage until it is to be used again, as for instance by wrapping repeatedly around its sides with string, after the manner of printers in temporarily securing together any type composition,

whether of single types or lines of type 65 This is made feasible by the provision of the pieces 9 at the ends, as above described. When the form is to be used for printing, it is properly mounted in the press in single column, or with other columns, as 70 the case may be, and locked up the same as any other composition. When so locked up, the type-bars or lines will be held firmly on their backing by the clip-rules 11, which latter, of course, will be held firmly in position 75 for performing this function by the usual clamping means around the sides of the form.

My invention thus affords a simple means for preserving any composition likely to 80 have a future limited use, without the disadvantage of storing large quantities of type metal. In a large printing establishment, especially where there are printed books or similar publications, the demand for which 85 is indeterminate at the printing of the initial edition, there is generally the desire to retain the composition pending the outcome of the publication of the first edition; yet a desire to avoid the expense of electrotyping a composition that may or may not be later required. Therefore, in such establishments as this, the amount of type metal in storage frequently grows to such an extent as to become a very undesirable proportion 90 of unproductive capital of the establishment. With my invention it will be seen that by far the greater proportion of this type metal is either withdrawn or withheld from the composition, with the result that 95 the type metal necessarily used is of such a small amount as to not be objectionable in the above respect, in case it is desirable to retain the work in form for a considerable period of time for the reasons above set 100 forth, or for any other reasons. At the same time, the utility of the form for printing is in no wise impaired, nor is there any material increase in inconvenience of handling it in making ready for the next edition. 110

Having fully described my invention, what I claim as new and desire to secure by Letters Patent is:

A printing form comprising a plurality of 115 separate and distinct single type-lines or bars, each of less than standard-type height, a backing for said lines or bars with plane upper and lower sides and plane upright sides and ends, to hold said bars at said height, each of said lines or bars having at 120 one end a lug with its upper surface inclined downwardly out toward the end of the line or bar, clip-rules, each comprising a flat upright part, lying flat along the respective upright side of the backing, and having a 125 part extending inward over and engaging with the inclined upper sides of the respective lugs, and flat pieces at the upright ends

of the backing extending up along the sides of the terminal lines or bars, and having the end parts of their upper edges inclined to aline with the upper sides of said lugs, and 5 said clip-rules having their inwardly extending parts engaging with these inclined end parts of said flat pieces, whereby said lines or bars are held from upward, endwise or lateral movement on said backing, and whereby said flat pieces are held against end- 10 wise or upward movement relative to said backing and said lines or bars.
